UNITED STATES PATENT OFFICE.

ANDREW RATHBONE, OF WARRINGTON, ENGLAND.

DRAW-PLATE FOR DRAWING WIRE.

No. 799,803.

Specification of Letters Patent.

Patented Sept. 19, 1905

Application filed March 7, 1905. Serial No. 248,806.

To all whom it may concern:

Be it known that I, ANDREW RATHBONE, a subject of the King of England, residing at Grappenhall, Warrington, in the county of 5 Lancaster, England, have invented new and useful Improvements in Draw-Plates for Drawing Wire, of which the following is a specification.

This invention has reference to draw-plates or "wortles" for drawing wire; and it has for its object and effect, primarily, to provide an improved draw-plate or wortle which shall not be so liable to become bowed and its life, correctness, and utility is generally increased; 10 and it has primarily for its object to prolong the life of such plates or wortles and render them easier to work. In practice this bowing of wortles or draw-plates takes place to a very great extent, and when plates are pricked or drilled in the ordinary way—that is, the 15 holes all pricked or drilled on one side—only one side of the tool is "spread" in "battering," with the result that the area of the face becoming greater on one side than the other 20 or the plate or wortle becomes bow-shaped or bowed, which ultimately destroys the plate or makes it useless by either splitting itself or breaking off the ends of the punches, owing to the holes being out of shape. 25 Now, according to this invention, to obviate this bowing the plates or wortles are pricked or drilled with holes from both sides—that is 30

to say, the small portion of the draw-holes at which the actual drawing takes place will be on the opposite sides or faces of the plate—as 35 will also of course the larger portions or mouths of these holes.

A draw-plate according to this invention is illustrated in the annexed drawings, in which—

Figure 1 is a longitudinal section, and Fig. 40 2 a plan.

In the drawings, *a* represents the small portions of the draw-holes at which the actual drawing or reducing takes place, and it will be noted that the successive holes of a row 45 longitudinally are on the opposite sides or faces of the plate alternately, as above described, and the larger portions or mouths *b* being of course also on the opposite sides of the plate alternately. A plate thus constructed 50 possesses the characteristics and advantages herein specified.

What is claimed is—

A draw-plate having a plurality of holes therein, the small portions of some of said 55 holes being on opposite sides of the plate.

In testimony whereof I have signed my name to this specification in the presence of two subscribing witnesses.

ANDREW RATHBONE.
